UNITED STATES PATENT OFFICE.

WILLIAM McHARRY, OF CHELSEA, ENGLAND.

INTERNAL-COMBUSTION ENGINE.

Application filed February 25, 1926, Serial No. 90,556, and in Great Britain March 4, 1925.

My invention relates to two-stroke cycle internal combustion engines, and has for its object to provide an engine of this type which shall have higher volumetric efficiency than those at present in use.

A simple form of the invention is illustrated in the accompanying drawing.

The drawing is an end view partly in section of an eight-cylindered automobile engine, 10 arranged with two cylinders for each of four crankpins, the cylinders' centers being at right angles to the crankshaft. The section shows the arrangement of the gear operating on the crankpin section, and the operations are precisely duplicated on the other three cranks.

The main casting A comprises the cylinders, the top half of the crankcase, and the bearings carrying the crankshaft B. C is the oil sump, partly shown. An L-shaped connecting rod D is reciprocated by the crankshaft B, and has a link E attached to its shorter end. A piston F is attached to the link E and is thereby reciprocated in a cylinder F', this cylinder functioning as a gas pump. A cylindrical valve G, reduced in diameter at G', has the same motion as F, being connected to F so that although it has practically no end play it has a certain amount of lateral play. The valve G reciprocates in a bushed valve housing H, and H also serves to close the cylinder F'. A cap J encloses the end of the valve G and is fixed to H. A piston K is attached to the longer end of D and reciprocates in a cylinder K', this cylinder functioning as a working cylinder. A head L covers the cylinder K', and also carries the sparking plug which is not shown. M is an exhaust manifold. There are four ports through which the charge passes, being: a piston-controlled port 1 through which the charge is entered into the pump; a valve-controlled transfer port 2 which commences in the cavity of F' and passes across the valve housing H, terminating in the cavity of K'; a piston-controlled main exhaust port 3, which is open to the manifold M; and a valve-controlled auxiliary exhaust port 4, which commences in K', passes across the valve housing H, and is then continued through the main casting A to the manifold M. As the continuation of the port 4 to the manifold M is not on the section line it is not therefore shown, only at N where it passes through the water jacket.

55 The rotation of the engine as shown is clockwise.

The operation of this engine is as follows, comprising the passage of a charge through the engine:—

The piston F on its downstroke causes a 60 partial vacuum in the cylinder F', and on the port 1 being uncovered a charge enters this cylinder. On the port 1 being closed by the return of the piston the charge is compressed to about twenty-five per cent of its volume, 65 which is the state of affairs as illustrated. It will be seen that the reduced diameter of the valve at G' is about to register the port 2 with the cylinder K', and thus permit the charge to be transferred from the cylinder 70 F' to the cylinder K'. The transfer continues until the piston K overruns the port 2, and the transfer is completed, the piston F being at about the end of its instroke. At the moment of the piston K overrunning the port 75 2 this piston has about another ten per cent of its stroke to go to reach the end of the compression. Ignition is effected by any convenient means, and the piston K commences its outward power stroke. During the outstroke of the piston K, on its uncovering the ports 2 and 4 respectively there is no loss as the valve G seals these ports. Towards the end of the outstroke of the piston K it uncovers the port 3 and the main exhaust takes 80 place, until on its instroke the piston K overruns the port 3 and closes it. Following the main exhaust is the auxiliary exhaust which is caused by the valve G' registering with the port 4, and this is continued until the valve 85 G' moves out of register with the port 4, by which time the piston K has travelled about seventy per cent of its instroke, and immediately before the state of affairs illustrated. At this point the passage of a charge through 90 the engine is complete.

I claim:

The combination in a two-cycle internal combustion engine, of a compression cylinder and a power cylinder arranged side by side, 100 pistons in said cylinders; a tubular extension integral with the compressor piston; a discharge passage between said compressor cylinder and said power cylinder; a main exhaust port and an auxiliary exhaust passage 105 in said power cylinder; said tubular extension controlling the opening and closing of both of said passages independently of the main exhaust port in the power cylinder.

WILLIAM McHARRY.
